VINCENT BENDIX, OF CHICAGO, ILLINOIS, AND LUDGER E. LA BRIE, OF SOUTH BEND, INDIANA, ASSIGNEES TO BENDIX BRAKE COMPANY, OF CHICAGO, ILLINOIS, A CORPORATION OF ILLINOIS.

BRAKE SHOE.

Application filed December 27, 1926. Serial No. 157,104.

This invention relates to brake shoes and is illustrated as embodied in shoes for an internal expanding automobile brake. An object of the invention is to provide improved constructions for such shoes, especially with a view to increasing their strength and facilitating their manufacture.

Various features of novelty relate to building up the shoe from an arcuate band and a separate web member by forming the web member with inclined tongues secured to the face of the band but with the tongue at the end of the shoe flat against the face of the band so that the web at that point is at right angles to the band, to an improvement in the cam-engaging thrust member at the end of the shoe so that it may be embraced between a cam flange and the cam bracket to hold the shoe against lateral movement, to stiffening the anchored end of the shoe by integrally continuing a narrowed part of the band along the pivot arm of the shoe, to stiffening a pair of spaced arms on the shoe which are intended to straddle part of an adjacent shoe by integrally continuing an outer band and preferably forming the band to embrace a part of the adjacent shoe to support it against the lateral movement, and to a novel arrangement of bearing washers secured to part of the shoe to embrace a pivot for the shoe.

The above and other desirable features of construction will be apparent from the following description of the illustrative embodiment shown in the accompanying drawing, in which:

Figure 1 is a vertical section through the brake just inside the head of the drum, and showing the novel shoes in side elevation;

Figure 2 is a partial section on the line 2-2 of Figure 1 showing the novel cam plates;

Figure 3 is a partial section on the line 3-3 of Figure 1 and showing a steady rest for one of the shoes;

Figure 4 is a partial elevation of the center shoe, looking in the direction of the arrows 4-4 of Figure 1 and showing the arrangement of the above-described tongues;

Figure 5 is a similar elevation at the end of one of the end shoes, looking in the direction of the arrows 5-5 in Figure 1;

Figure 6 is a partial section on the line

6-6 of Figure 1 and showing the connection between two of the shoes;

Figure 7 is a section through the center shoe on the line 7-7 of Figure 1;

Figure 8 is a section through one of the end shoes on the line 8-8 of Figure 1;

Figure 9 is a partial section on the line 9-9 of Figure 1 and showing the anchorage of the brake;

Figure 10 is a partial section on the line 10-10 of Figure 1 and showing the embracing of a part of one shoe by the end of the other;

Figure 11 is a section on the line 11-11 of Figures 1 and 10 and showing the overlapping of the two shoes; and

Figure 12 is a section on the line 12-12 of Figure 1 and showing the construction at the end of the shoe.

The illustrated brake includes a rotatable drum 20, at the open side of which is arranged a stationary support such as a backing plate 22, and within which are arranged three brake shoes 24, 26, and 28. The shoe 24 is anchored on a pivot 30 between the ends of the shoe 26, while the shoe 26 is anchored on a pivot 32 between the ends of the shoe 24, and the shoe 28 is connected to the unanchored end of the shoe 26 by a floating pivot 34. The brake is applied against the resistance of a return spring 36 by means such as a double cam 38, the shoe 26 being applied by the shoe 28 against the resistance of an auxiliary return spring 40. The idle position of the shoe 26 is determined by a stop in the form of a grooved eccentric 42 interlocking with a flange 44 on the end of a floating pivot 34. The shoe 28 is shown as being provided with a steady rest including a pin 46 secured to the backing plate 22 and projecting through an opening in the shoe 28, and having at its end a pair of washers

48 on opposite sides of the shoe and held by a cotter pin 50. A coil spring 52 is sleeved on the pin 46 and holds the shoe yieldingly as far outwardly as the cotter pin 50 will permit. The present invention relates to various novel structural features of the brake shoes, whether or not used in this particular brake.

Each of the brake shoes is built up of an outer arcuate band 54, to which the brake lining 56 is riveted or otherwise secured,

and one or more separate stiffening members spot-welded or otherwise secured to the inner face of the band. Each of the shoes 24 and 28 has a single stiffening member 58 radially slotted to form inclined tongues 60 which are laterally bent in opposite directions so that, in effect, as shown in Figure 5, they form two staggered series of tongues 60 engaging and spot-welded or otherwise secured to the inner face of the outer band 54. At the ends of the shoes, however, the member 58 extends perpendicularly against the inner face of the band 54, and is then turned at right angles to form a separate tongue 62 engaging the inner face of the band 54. Thus the band 54 is supported at its center at the end of the shoe.

Shoe 26 is provided with two stiffening members 64 and 66 which are formed with alternately bent or staggered tongues 68 corresponding to the tongues 60. As best shown in Figure 4, the corresponding tongues 68 on the two stiffening members 64 and 66 are preferably bent in the same direction throughout the greater part of the shoe. However, the two end tongues 70 are both bent outwardly at right angles the same as the tongue 62, so that the ends of the stiffening members 64 and 66 are perpendicular to the inner face of the band 54 of shoe 26.

The upper ends of the shoes 24 and 28 are provided with cam or thrust plates 72 extending across and centrally braced by the ends of the stiffening members 58. Each cam plate then extends back to form two parallel parts and is finally extended into engagement with and secured to the opposite sides of the member 58, so that each cam plate 72 in effect forms a box-section adapted to be embraced between the bracket 74, in which the cam-shaft is journaled, and a flange 76 on the end of the cam 38. The ends of the shoes, where they are mounted on the pivots 30, 32, and 34, are preferably provided with bearing washers 78 which are drawn outwardly to form short sleeves adapted to be journaled on the pivots, and which are notched at their edges to form sets of radially projecting tongues alternating with notches or spaces. Where the shoes are provided with these washers on opposite sides, as for example the shoe 24 as shown in Figure 9, the notch or opening in the washer on one side is arranged opposite the tongue of the washer on the opposite side, so that the tongue may be spot-welded to the stiffening member 58 with only two thicknesses of metal to be dealt with.

The stiffening member 58 of each of the shoes 24 and 28 is continued beyond the lower end of the shoe to form an arm adapted to be mounted on the pivot 30 or 34, and we prefer to stiffen this arm by integrally continuing a narrowed portion of the band 54

substantially to the end of the shoe. This part of the stiffening member 58 projects at right angles to the member 54, as shown in Figure 11, and is formed with a flange 80 spot-welded or otherwise secured to the inner face of the narrowed continuation of the band 54. It will be seen that both of the shoes 24 and 28 project past the corresponding ends of the shoe 26, the pivot arms at the lower ends of these shoes being straddled by the ends of the stiffening members 64 and 66. The shoe 26 is also reinforced by continuing the band 54 along the pivot arms formed by continuing the members 64 and 66 at the right end of the shoe and offsetting them within the curve of the shoe to be mounted on the pivot or anchor 32. We prefer, however, to form an opening 82 between these continuations of the band 54, for the lower end of the shoe 24, and at the extreme end of the band 54 of shoe 26 we provide a pair of lugs 84 projecting from opposite sides of the opening 82 into engagement with the opposite sides of the member 58 to position the shoe 24 laterally and support it against lateral movement.

While one illustrative embodiment of the invention has been described in detail, it is not our intention to limit its scope to that particular embodiment or otherwise than by the terms of the appended claims.

We claim:

1. A brake shoe built up of an arcuate lining-carrying band and a web member secured to one face of the band and serving to stiffen it, and in which said web member is throughout a considerable part of its length formed with inclined tongues engaging and secured to said face of the band, and at its end extends substantially perpendicular to the band with a tongue at right angles to said end engaging and secured to said face of the band.

2. A brake shoe built up of an arcuate lining-carrying band and a web member secured to one face of the band and serving to stiffen it, and in which said web member is throughout a considerable part of its length formed with inclined tongues engaging and secured to said face of the band, and at its end extends substantially perpendicular to the band.

3. A brake shoe built up of an arcuate lining-carrying band and a web member secured to one face of the band and serving to stiffen it, and in which said web member is throughout a considerable part of its length formed with staggered series of tongues inclined in opposite directions into engagement with one face of the band, and in which said web member at its end extends perpendicularly from said face of the band.

4. A brake shoe having a stiffening web, and a thrust member at the end of the shoe

- extending across and centrally engaged by the end of said web, then extending at both sides of the shoe in parallel planes parallel to said web away from the end of the shoe, 5 and finally extended into engagement with and secured to the opposite sides of said web, thus forming a box section thrust member with parallel sides adapted to be embraced between a cam flange and a cam bracket to hold the shoe against lateral movement.
5. A brake shoe comprising an outer arcuate lining-carrying band, and a curved stiffening web member secured along its outer edge to the inner face of the band and at one end of the shoe continued as a pivot arm offset substantially within the curve of said band, the band being narrowed in width and integrally continued along said offset arm to stiffen it.
10. 6. A brake shoe comprising an outer arcuate band and a pair of separate spaced stiffening webs secured to one face of said band and integrally continued at one end of the shoe as spaced inwardly-offset pivot arms adapted to straddle a part of an adjacent shoe, the band being integrally continued along said spaced arms and slotted to embrace said part of the adjacent shoe and support it laterally.
15. 7. A brake shoe comprising an outer arcuate band and a pair of spaced stiffening webs projecting from one face of said band at least at one end of the shoe and integrally continued at said end of the shoe as spaced inwardly-offset pivot arms adapted to straddle a part of an adjacent shoe, the band being integrally continued along said spaced arms and slotted to embrace said part of the adjacent shoe and support it laterally.
20. 8. A brake shoe comprising an outer arcuate band and a pair of spaced stiffening webs projecting from one face of said band at least at one end of the shoe and integrally continued at said end of the shoe as spaced inwardly-offset pivot arms adapted to straddle a part of an adjacent shoe, the band being integrally continued along said spaced arms and slotted to embrace said part of the adjacent shoe and support it laterally.
25. 9. A brake shoe comprising one face of said band at least at one end of the shoe and integrally continued at said end of the shoe as spaced inwardly-offset pivot arms adapted to straddle a part of an adjacent shoe, the band being integrally continued along said spaced arms and slotted to embrace said part of the adjacent shoe and support it laterally.
30. 10. A brake shoe having a part formed with an opening, and a pair of bearing washers secured to opposite sides of said part in line with said opening, the washers having outwardly-extending tongues separated by openings and being arranged with the tongues of one opposite the openings of the other, said tongues being spot-welded to said part of the shoe.
35. 11. A brake shoe having a part formed with an opening, and a pair of bearing washers secured to opposite sides of said part in line with said opening, the washers having outwardly-extending tongues separated by openings and being arranged with the tongues of one opposite the openings of the other.

In testimony whereof, we have hereunto signed our names.

VINCENT BENDIX.
LUDGER E. LA BRIE.
